THIS ATTORNEY

UNITED STATES PATENT OFFICE.

FREDERICK W. GURNEY, OF ROAN MOUNTAIN, TENNESSEE.

WOOD PULLEY.

SPECIFICATION forming part of Letters Patent No. 680,994, dated August 20, 1901.

Application filed July 24, 1899. Serial No. 724,884. (No model.)

To all whom it may concern:

Be it known that I, FREDERICK W. GURNEY, a citizen of the United States, and a resident of Roan Mountain, in the county of Carter 5 and State of Tennessee, have invented certain new and useful Improvements in Wood Pulleys, of which the following is a specification.

My invention relates to the construction of 10 wooden pulleys, particularly to the class of separable or "split" pulleys; and its object is to simplify and improve the construction, secure a better grip upon the shaft, reduce the cost of manufacture, and render the pulley 15 more durable and substantial.

My invention consists in centering the pulley upon a shaft by means of sets of duplicate parallel slats or bars, each of which is built into the rim at one end and has an over- 20 lapping hub-butt at the other end, making a practically solid hub and materially increasing the grip of the pulley upon the shaft.

It also consists in certain other features of construction and combinations of devices, all 25 as will hereinafter more fully appear, and be particularly pointed out in the appended claims.

In the accompanying drawings, Figure 1 is a side elevation of a pulley constructed in 30 accordance with my invention. Fig. 2 is a central vertical section taken on the line xx , Fig. 1. Fig. 3 is a plan of the pulley. Fig. 4 is an enlarged sectional view taken on the line yy , Fig. 1, and illustrating the manner 35 of lap-jointing the halves of the pulley, as well as the method of building the slats into the rim. Fig. 5 is an enlarged fragmentary face view of the pulley, showing the halves separated; and Fig. 6 is an enlarged per- 40 spective view of one of the clamping plates or bars used to bind the pulley to a shaft.

Throughout the several views like parts are indicated by like numerals.

The rim 1 is built up of a series of wooden 45 rings or layers 2 in a well-known manner, each layer being composed of a series of segments 3, placed end to end and preferably breaking joints, as shown. The rim is supported upon wooden slats, each terminating 50 at its inner end in a butt 5, having a spoke portion 4, and at its outer end being formed with a head 6, which is built into the rim.

Each slat is preferably a duplicate of the others, and in each butt is a centering cut-away 7, which may fit directly upon a shaft, 55 if the latter is of suitable diameter, or else upon the usual wooden half-bushings 8, of cylindrical form, whose inner diameter is such as to fit the shaft 9. In either case it will be noted that the cut-away 7, whether of the illustrated semicircular shape or of some other suitable shape, serves to center the pulley directly upon the shaft or cylindrical support. As usual, bushings of various thicknesses may be supplied for each pulley, so 60 that it may be readily centered upon shafts of various diameters.

The slat-butts lie one against another to form a virtually solid hub for the pulley, and the cut-aways or recesses 7, being all in line, 70 form a central opening for the shaft. The length of bearing thus given the pulley upon the shaft is equal to the aggregate thicknesses of the butts and about equal to the width of the pulley-face, thus both affording 75 an increased shaft-gripping surface, and insuring the true centering of the pulley upon the shaft. It will be noted that all strains are in direct lines from all parts of the solid hub to the rim. 80

The slats are alternating, with their heads extending in about opposite directions, so that spaces are left between the spoke portions but not between the hub portions. Three slats are shown in the upper portion 85 of the half-pulley at Fig. 2 and four in the lower portion. A pulley with a face not so wide as this one may be constructed with fewer slats and one with a wider face with more slats; but in all cases the preferred 90 construction is to arrange one more slat in one portion of each half-pulley than are arranged in the opposite portion thereof. When the halves are placed together to form the complete pulley, the larger group of slats in 95 one pulley-half is placed next to the smaller group of slats in the other pulley-half, thus giving the pulley a running balance (so that it rotates smoothly, lasts longer, and is better adapted to high speeds) and also equalizing the strength of the pulley at the opposite portions near the lap-joints. 100

The thickness of each slat at its head portion, and preferably throughout its length, is

preferably equal to the thickness of one of the segments 3 of which the rim layers 2 are built up, the head 6 being built into the rim and serving as a portion of the face or belt 5 surface of the rim. In building up the pulley each spoke-head 6 is preferably glued or cemented to the rim layers on each side of it and is also separately nailed or screwed to its adjacent rim layer 2, as at 10, Fig. 4. 10 Since a layer is placed over each nail or screw after it is driven home, it is impossible for the latter to work loose.

The spoke-heads and layers are still further secured together by means of headed 15 bolts 12, each passing through the series of combined layers and heads and provided with a binding-nut 13. Finishing or edge layers 11 are added to the rim, each provided at proper points on its inner side with recesses 14 to form housings for the bolt-heads 12 and nuts 13. By this construction the pulley-rim is provided with unbroken edges or sides without projecting heads and nuts, which would be a source of danger to a workman when slipping a belt over the pulley. 25 The nuts cannot work off from the bolts, nor can the bolts work out.

The rim halves are united by lap-joints, as shown at Fig. 5. The half-pulleys are not 30 made right and left, but all alike, so that any half-pulley can be readily joined to any other half-pulley of the same dimensions. This will be understood by reference to Fig. 1, where the line of division is indicated by full 35 lines at *a a*. By this construction not only is the process of manufacture simplified and cheapened, but in case only one half of the pulley becomes damaged at any time when in use or in transit it can be replaced without 40 the necessity of providing an entire new pulley.

When the pulley halves are assembled, a fastening-pin 15 is passed through a hole 16, bored transversely through each set of interlocking segments, thus producing a substantial 45 union of the two halves and rendering the pulley about as strong at this as at other portions.

For clamping the butts to the shaft headed 50 bolts 17 are provided, each of which extends transversely through both sets of butts (each set forming a half-hub) and binding them firmly to the shaft by means of nuts 18. The bolts are shown in section at Fig. 2, and it 55 will be noted that a passage-way for the bolts is made without unduly weakening any butt, as each bolt passes between two butts, in the side faces of which half-round grooves are cut to receive the bolts, the groove in one 60 butt matching the groove in the adjoining butt. No butt is cut away at any point more than half the thickness of a bolt.

To avoid injury to the butts and to bind them all firmly to the shaft, plates 19, suitably 65 perforated at 20 for the entries of the bolts, may be placed between the butts and the bolt-heads and nuts.

The butts are capable of a slight edgewise movement, altogether or as a unit, toward the pulley-axis when the nuts are turned up; 70 but it will be perceived that such edgewise flexibility of the slats is not such as to produce a weak pulley, and, further, that the flexing of the slats when turning up the nuts tends not only to bind the two halves of the 75 pulley-rim firmly together, but also to stiffen the entire structure. Any desirable degree of flexibility may be obtained by cutting away the edges of the slats at the portion near their outer ends, as at 23. A space or 80 clearance at 22 is left between the half-hubs when they are fixed upon the shaft, so as to insure their being clamped thereon without liability of nullifying the action of the nuts by pressing against each other instead of 85 against the shaft.

If desired, the plates 19 may be provided with overhanging ears 21, so that each plate, with its ears, forms a clip, confining the slats against lateral motion and adding to the substantial character of the contrivance. The butts may also be glued and nailed or bolted together, as at 21^X. It will be noted that by passing the bolts directly through the hub all of the slats are firmly clamped to the shaft or 95 cylindrical support.

In mounting the pulley the halves are first placed in position upon the shaft or bushings. One set of hub-bolts is then drawn up until the rim-pin 15 can be inserted on that side. 100 Then the bolts are drawn up on the other side of the shaft until the opposite pin 15 can be inserted. Then all bolts are tightened until the hub is clamped firmly to the shaft. To remove one of the rim-pins 15, the bolts upon 105 the opposite side of the shaft should first be loosened.

Each slat or bar is of a length greater than the radius of the pulley and extends from one side of the pulley past the center thereof, but 110 not over to the opposite side, the extended portion being preferably only great enough to overlap the oppositely-projecting next adjacent or alternately-arranged slat or bar and at about the junction of its arm 4 and butt 5. 115 It will be noted that each arm terminates at its inner end in a hub-butt and at its outer end supports the rim at about the point of union of the pulley halves, making a firm construction, that the rim is supported upon two 120 equipoised sets of alternately-arranged slats, each set having the same number of slats, one set extending across the pulley upon one side of its axis and the other set extending across the pulley on the other side of its axis, whereby 125 a running balance is secured, that each half-rim is supported upon slats provided at their inner ends with overlapping butts and extending alternately at their outer ends to opposite portions of the rim, and that each 130 half-hub is virtually solid or continuous and composed wholly of a series of similar and overlapping spoke-butts.

The use of duplicate slats throughout en-

ables a reduction to be made in the cost of manufacture without detracting from the usefulness of the pulley.

It will be seen that my pulley is of the class in which the system of spoke-arms as an entirety extends crosswise or diametrically from one side to the other of the pulley, one set of the cross-bars in said system being arranged upon one side of the center of the pulley and the other set upon the opposite side, and all of the spokes being preferably parallel. The spokes are attached to the rim at their outer ends only. Their inner ends terminate in butts which cross the hub, or, in other words, the spokes terminate beyond the center of the pulley. The butts are provided with centering notches or cut-aways upon their inner side edges. The spokes are arranged to project toward one another diametrically of the pulley and to alternate, being arranged in different parallel planes and overlapping at their butt ends, whereby all of the notches in their side edges are brought into line axially of the pulley. The butt portions may all be arranged in face contact, forming a series of butts extending axially of the pulley, so as to produce a solid hub or half-hub, which is preferably formed of butt portions solely, without the intervention of spacing or filling blocks. My spokes are clamping-spokes, and taken altogether form a clamping device which is distinct from the pulley-rim, the clamping action being secured by springing together the opposite halves of the system of cross-bars, which is done without distorting the rim or throwing the pulley out of center. It will also be seen that the full thickness of each spoke clamps upon the shaft, and hence the spoke transmits a maximum of power directly from the shaft to the rim, or vice versa.

Although I have shown and described only my preferred construction, I do not intend to limit the scope of my invention thereto, since without departing therefrom many variations may be introduced in the detail construction. Many portions of my invention are also applicable to solid or non-separable pulleys.

What I claim as new, and desire to secure by Letters Patent, is—

1. A pulley comprising a rim and two series of oppositely-projecting alternating wooden spoke-arms, each arm being secured at one end only to the rim and terminating at its other end beyond the center of the pulley, and being also provided at its inner side or edge with a cut-away, whereby the pulley may be centered upon a cylindrical support.

2. A pulley comprising a rim and two series of oppositely-projecting alternating wooden spoke-arms, each arm being at one end built into the rim and extending crosswise of and terminating just past the center of the pulley, and having at its side a centering cut-away or notch, and all of the oppositely-projecting alternating butt-ends overlapping at the cen-

ter of the pulley and being arranged in contact face to face, and with their notches or cut-aways all in line axially of the pulley, and the entire series of arms thus constructed and arranged forming a practically solid pulley-hub.

3. A pulley comprising a rim built up of a series of similar layers, and a series of oppositely-projecting wooden slats, each terminating at one end in a head and at the other end in a butt and being of the same thickness as a rim layer, each head being built into the rim as if it were part of a layer, and all of the butts overlapping and terminating centrally of the pulley and so constructed as to form the pulley-hub.

4. In a pulley, the combination with a rim, of sets of oppositely-projecting wooden slats terminating in overlapping hub portions and extending crosswise of the pulley, on one side of the axial line thereof; other sets of oppositely-projecting slats terminating in overlapping hub portions and extending crosswise of the pulley, on the opposite side of the axial line thereof; a clearance-space being left between the two sets of slats at their hub portions when they are clamped upon a cylindrical support; and means for clamping the hub portions upon a cylindrical support.

5. In a pulley, the combination with a rim of a diametrical cross-bar comprising half portions arranged upon opposite sides of the center of the pulley, and each half portion consisting of a series of oppositely-projecting alternating slats, the outer ends of which are built into the rim, and the inner butt-ends of which overlap and extend past the center of the pulley, said butt-ends being provided with notches or cut-aways upon their inner edges or sides and at the center of the pulley, and means for binding the opposite series of notched butts upon a cylindrical support.

6. In a pulley, the combination with a rim of a series of oppositely-projecting alternating wooden slats built into the rim and terminating in overlapping centering-butts having notches or cut-aways in their side edges, the slats being cut away at their outer portions, as at 23, to increase their flexibility, and means for binding the butts upon a cylindrical support.

7. In a pulley, the combination with a rim, of a series of oppositely-projecting alternating wooden slats fixed only at the points of union with the rim, each slat extending at its free end beyond the axial line of the pulley, overlapping the adjoining slat, and provided with a centering cut-away, and means for applying compression to the slats at their free ends in a direction about crosswise of their length, whereby the free ends are forced toward the pulley-axis, and caused to grip their common cylindrical support.

8. A split pulley, each half of which is constructed with a series of oppositely-projecting alternating wooden slats, each of which

terminates at its inner end in a hub-butt, and at its outer end is joined to the rim at about the point of union of the half-rims.

9. A split pulley constructed with duplicate halves, each half comprising a rim portion and a series of oppositely-projecting alternating wooden slats terminating about centrally of the pulley in a solid half-hub formed by notches cut in the side edges of the terminal portions of said slats.

10. A pulley comprising a rim and two equi-poised sets of oppositely-projecting alternating wooden centering-slats, each set having the same number of slats, one set extending across the pulley upon one side of its axis, and the other set extending across the pulley upon the other side of its axis, and each set of slats having a series of alined notches formed in their side edges.

11. A split pulley each half whereof comprises a rim portion and a series of oppositely-projecting wooden slats which extend crosswise of the pulley, each slat terminating at one end in a hub-butt and at the other end being joined to the rim, and the slats extending alternately from the hub to opposite portions of the rim, there being more slats extending in one direction than in the other; the construction being such that when the

half-pulleys are united the portion of one of the halves having the fewer slats may be placed next the portion of the other half having the greater number of slats, whereby a running balance is secured.

12. In a pulley, the combination with a rim, of sets of alternate wooden slats arranged on

opposite sides of the pulley-axis, each slat joined at one end to the rim and terminating at the other end in a centering-butt, plates 19, having ears 21 for confining the butts, and bolts 17 coöperating with the plates to clamp the butts upon a cylindrical support.

13. In a pulley, the combination with a rim, of sets of alternate wooden slats arranged on opposite sides of the pulley-axis, each slat being joined to the rim and provided with a centering portion, the slats having matching bolt-grooves cut in their sides, plates 19, and bolts 17 passing between the slats within said grooves and coöperating with the plates to clamp the slats upon a cylindrical support.

14. In a pulley, a set of parallel slats built into the rim at their outer ends and extending crosswise inwardly from one side of the rim and terminating at their inner ends about centrally of the pulley in hub-butts, a second set of parallel slats also built into the rim at their outer ends and extending crosswise inwardly from the opposite side of the rim and alternating with the first set of slats and terminating at their inner ends about centrally of the pulley in hub-butts, the hub-butts of both alternating sets overlapping and contacting facewise and constructed to form an elongated half-hub.

Signed at Roan Mountain, in the county of Carter and State of Tennessee, this 17th day of July, A. D. 1899.

FREDERICK W. GURNEY.
